UNITED STATES PATENT OFFICE.

HARRY M. BLAETZ, OF PHILADELPHIA, PENNSYLVANIA, ASSIGNOR TO ROYAL ELECTROTYPE COMPANY, A CORPORATION OF PENNSYLVANIA.

HOLDER FOR ELECTROPLATING.

1,354,234.

Specification of Letters Patent. Patented Sept. 28, 1920.

Application filed January 17, 1920. Serial No. 352,030.

To all whom it may concern:

Be it known that I, HARRY M. BLAETZ, a citizen of the United States, and resident of the city of Philadelphia, in the county of Philadelphia and State of Pennsylvania, have invented certain new and useful Improvements in Holders for Electroplating, of which the following is a specification.

This invention relates to certain novel and useful improvements in a holder adapted to be employed in the making of lead-molding electrotypes.

In the printing art, in the making of lead-molding electrotypes, it is the practice to impress a thin flat sheet of lead against a copper engraving, etching or other original for the purpose of reproducing the printing face in the lead sheet. This lead sheet is then nailed to a board or metal plate covered with wax to prevent the deposition of the electroplating material on such supporting board or plate. The board with the lead plate fastened thereon is then suspended in the electroplating bath, the electroplating solution being deposited by the usual method upon the matrix face of the lead sheet until a metallic shell is formed which is subsequently removed from the lead sheet and backed up by any well known method to form an electroplate. After a shell has been made, it is necessary to scrape off particles of copper or nickel which have been deposited on any spots or places on the supporting board which have not been made thoroughly non-conductive by dipping in the wax. It is then necessary to re-dip the board in the wax bath, or go over the board with a hot iron to cover up nail holes which have been made in the nailing of sheets of lead to the same.

Heretofore, it has been the practice to nail or otherwise fasten a number of small molded or matrix lead sheets against the board preparatory to suspending the latter in the bath, the sheets having been individually cut to the required size. Inasmuch as the nails, studs or other fastening devices holding the lead sheets to the board are of metal, and accumulation or deposition of the electro-plating material is liable to take place upon these metallic points.

Furthermore, the practice of cutting the lead sheets into small sections and then mounting the same upon and subsequently

removing them from the board is both time-consuming and expensive.

To obviate above objections I have provided a holder for a lead plate which is composed of such material that it is impossible for an electroplating solution to be deposited thereon and furthermore this board is of itself of sufficient weight and stability that it will hang in a true vertical position in the bath without resorting to the use of weights or the like.

Another advantage incident to my holder is that a relatively large lead sheet may be readily mounted upon and removed therefrom. This feature enables me to lay out a number of cuts, etchings or the like in a single form, with due regard to the position that the printed matter is to occupy upon the paper. I may then take an impression of this large assembled form upon a single lead sheet, suspend the sheet from my holder or electroplate in the usual manner, thereby obviating the necessity of fastening small individual impressed lead sheets upon the board.

Another object of my invention is to form the board of such material that it will maintain its shape indefinitely without warping, buckling or shrinking, which will possess the desired features of strength, durability and convenience. I also equip my holder with means whereby the lead sheet may be easily and quickly mounted and removed without nailing, screwing or the like.

With the above recited objects, and others of a similar nature in view my invention consists in the construction, combination and arrangement of parts set forth in and falling within the scope of the appended claims.

In the accompanying drawings:

Figure 1, is a perspective view of my improved holder, and showing a lead plate mounted thereon in the position it occupies on the holder for treatment in the electroplating bath.

Fig. 2, is a vertical cross sectional view taken through the upper portion of the holder of Fig. 1.

Fig. 3, is a horizontal cross sectional view taken through the holder.

Fig. 4, is a perspective view of the upper portion of the board and showing a modified form of clamp.

Referring now to the accompanying drawings, in detail, the letter A designates

the holder as an entirety, and it comprises a body portion 1 which is in the nature of a flat board-like structure. This body portion is preferably made from a composition 5 of fiber and a synthetic resin, such as a phenolic condensation product, of which there are a number of well known varieties upon the market, of which might be mentioned bakelite and condensite. In the 10 preparation of this body portion the composition, composed of the fiber and phenolic condensation product, is pressed and heated until the phenolic condensation assumes its reacted state when, as is well 15 known it is in a hard, set and substantially infusible form. Owing to the character of the materials employed the body portion will be much heavier than a board of wood or fiber, and will of its own weight hang 20 vertically in the solution or bath. In addition such a board will possess smooth, hard, polished and impervious faces, and having no affinity for an electroplating solution, the latter will not accumulate or deposit 25 upon this board-like body portion. At the side edges of the body portion I provide the parallel retaining guides B. In the present instance each guide is composed of a relatively narrow strip 2 fastened to the 30 body portion, and a relatively wide strip 3 imposed upon strip 2, so that an open-faced slot 3 is formed at the inner edge of each guide. Suitable studs or rivets 4 are employed to fasten the strips to each other 35 and to the body portion, the heads of these studs being also preferably covered with phenolic condensation product as at 5 to prevent the deposit of electroplating material thereon. The construction of the guides 40 B shown herein is merely by way of illustration, as these guides may be of any desired form, for example, they may be integral with the body, in the molding operation of making the latter, or they may be 45 in the nature of rabbeted strips, or they may be made adjustable to each other so that they can be shifted toward and from the center line of the board, in any well known manner, as by a slot and stud arrangement, so 50 as to accommodate lead sheets of different widths. In actual practice the lead sheet which is shown at L is slipped beneath the guides B in a face to face contact with the body portion as is shown in Fig. 1.

55 In order to hold the lead sheet suspended in the position shown in Fig. 1, I may employ a suitable clamp indicated as an entirety by the letter C. In the present instance, the clamp shown in Fig. 2 comprises 60 a back strap 5 of any suitable material, such as metal, having its lower end formed with an off-set or flange 6 constituting a hook which engages with the slot 7 formed adjacent the top edge of the board A, and the 65 upper end of this back strap 5 is curled or

bent as at 8 to enable the clamp to be suspended from the usual hanger rod of the container of the electroplating bath. The other member of the clamp comprises a front strap 8, the upper end of which is 70 curled or bent as at 9 to form a handhold, and immediately beneath this curled portion the strap has a short flat section 10 which is adapted to lie in face to face contact with the adjacent section of the back 75 strap 5, and to be bolted or otherwise secured thereto as shown at 11. Immediately below this section 10 the front strap is bent outward and downward as at 12 forming an off-set, and immediately below 80 this off-set portion the strap extends straight or in parallelism with the back strap 5, as shown at 13, the lower end of this straight section 13 of the front strap being bent rearward at right angles to form 85 a hook-like edge or tooth 14 which is adapted to engage or press against the lead sheet. This engaging edge 14 of the clamp may be in the nature of a knife edge flange, or if desired this flange may be serrated as 90 will be readily understood. It will of course be evident that by uniting the front strap with the back strap as by the studs or rivets 11, and then providing the front strap with the off-set, a spring clamping 95 tongue is formed which will act to clamp or hold the lead plate in place upon the board. For the purpose of tightening and loosening the clamp I may provide a set screw 15 provided with the usual thumb nut 100 16. As will be evident from Fig. 1 when this clamp is in use it will retain the lead sheet in proper suspended position on the board and prevent such end dropping or falling of its own weight.

105 In Fig. 4, I have shown a modified form of clamp, of somewhat simpler construction. In this case the board, a portion of which is indicated at A', is provided with holes 17 for the reception of hooks by means 110 of which the board may be suspended from the hanger rod of the bath container. Intermediate these hooks I bolt to the board a metallic clamping strap 18, the studs for securing the strap being shown at 19. The 115 lower and longer end of the clamping strap illustrated at 20 is provided with an in-turned, beveled plate-engaging flange 21 which is adapted to grip the plate. As the rivets or studs 19 fastening the clamping 120 strap are located above the horizontal central line of the clamp, the lower end of the latter may be sprung or pressed upward to permit the insertion of the lead plate therebeneath, and when released the clamping 125 end will of course spring into plate clamping position.

130 In the course of operation the holder carrying the lead plate is placed in the metallic electroplating solution so that the lead plate

is in circuit as usual, such plate forming the cathode while the anode of course hangs a short distance from the cathode, and the clamp forms the connecting point between 5 the negative rod of the cathode and the cathode itself, and the electroplating deposit takes place in the ordinary manner.

After the electroplating has taken place the holder may be removed from the bath 10 and the lead plate attached simply by lifting the clamp and slipping the plate from beneath the guides.

It will be noted that I have provided an exceedingly simple yet efficient holder for 15 the purpose intended, and this holder is composed of a material which will retain its flatness of form and shape indefinitely, for it is not subject to warping, buckling or the like, while it possesses great wear-re- 20 sisting qualities.

While I have herein shown and described one preferred embodiment of my invention, I wish it to be understood that I do not confine myself to all the precise details of 25 construction herein set forth by way of illustration, as modification and variation may be made without departing from the spirit of the invention or exceeding the scope of the appended claims.

30 What I claim is:

1. A device of the class described comprising a flat body portion, retaining guides mounted thereon and a clamping member carried by the body portion and adapted to 35 hold a plate against the body.

2. A device of the class described comprising a body portion, parallel retaining guides located adjacent the side edges thereof and a clamping member carried by the 40 body portion and adapted to hold the plate against the body.

3. A device of the class described com-

prising a board-like body portion, slotted retaining guides carried by the body portion and a spring clamping member carried 45 on the body portion and adapted to engage and clamp the plate against such body portion.

4. A device of the class described comprising a body portion composed of a material including a hard and set synthetic resin, and plate clamping devices for removably holding a plate against the body portion. 50

5. A device of the class described comprising a relatively flat body portion of a composition of fiber and a hard and set phenolic condensation product, and means carried by the body portion for removably securing a plate against the body portion. 55

6. A device of the class described comprising a relatively flat body portion and a two part strap clamp carried thereby and provided with plate engaging projections.

7. A device of the class described comprising a board-like body portion, plate retaining guides carried thereby and a clamp having two strap-like clamping members carried by the body portion, one of said members being provided with a plate engaging 65 edge. 70

8. A device of the class described comprising a board-like body portion composed of fiber and a hard and set synthetic resin, parallel guide strips located at opposite side 75 edges of said body portion and a metallic spring clamp carried by the body portion and adapted to cooperate with the strips to retain a plate against the body portion.

Signed at city of Philadelphia, in the 80 county of Philadelphia and State of Pennsylvania, this 14th day of January, A. D. 1920.

HARRY M. BLAETZ.
